UNITED STATES PATENT OFFICE.

EDMOND KUHN, OF BROOKLYN, NEW YORK, ASSIGNOR TO REMINGTON PHONOGRAPH CORPORATION, OF WILMINGTON, DELAWARE, A CORPORATION OF DELAWARE.

SOUND REPRODUCER.

1,412,560.

Specification of Letters Patent. Patented Apr. 11, 1922.

Application filed May 18, 1921. Serial No. 470,698.

To all whom it may concern:

Be it known that I, EDMOND KUHN, a citizen of the United States of America, residing at Brooklyn, in the county of Kings and State of New York, have invented certain new and useful Improvements in Sound Reproducers, of which the following is a specification.

This invention relates to phonographs and like sound reproducing devices and has special reference to a sound volume regulating reproducer mounted for such instruments.

One principal object of the invention is to provide an improved sound volume regulating means for phonographs and the like.

A second important object of the invention is the provision of an improved reproducer mounting for such instruments so arranged that the volume of sound passing from the reproducer to the tone arm may be increased or diminished at will.

A third important object of the invention is to provide, in such a device, means to ensure a full volume of sound with each change of the needle unless such volume is wilfully reduced.

With the above and other objects in view, the invention consists in general of certain novel details of construction and combinations of parts hereinafter fully described, illustrated in the accompanying drawings, and specifically claimed.

In the accompanying drawings, like characters of reference indicate like parts in the several views, and:—

Figure 1 is a side elevation of a portion of a phonograph showing the improved arrangement of the tone arm and reproducer, the latter being shown on a disk record.

Figure 2 is an enlarged detail showing the reproducer raised in needle changing position.

Figure 3 is an enlarged detail partly in section on the line III—III of Figure 2.

Figure 4 is a section on the line IV—IV of Figure 3.

Figure 5 is a detail side view of the reproducer removed from the tone arm.

Figure 6 shows grouped details illustrating in side and end elevation the sound volume regulating valve.

In the embodiment of the invention herein illustrated there is employed a tone arm 10 which is mounted at 11 to swing horizon-

tally but is held against vertical movement. At the forward or free end of this tone arm is formed a bearing opening 12 having a horizontal axis at right angles to the axis of the tone arm and opening through said arm at each side thereof. This bearing opening opens at one side into the tone arm as shown at 13.

At 14 is a sound box of any preferred construction and having a tubular journal 15 extending from one side and provided with an opening 15' in one side which normally registers with the opening 13. Within this journal is mounted a sleeve valve 16 having a port 17 in one side thereof. This valve is closed at one end and the closed end is provided with an axial stem 18 which projects through a closure plate 19 screwed into an annular flange 20 surrounding the end of the journal opening 12. On the end of this stem is fixed a pointer or indicator 21 which traverses a series of graduations 22 formed around the edge of the closure 19. The rear end 23 of this pointer is extended and bent down beyond the periphery of the closure so that it may contact, under suitable conditions with a stop member 24 projecting from said closure.

For the purpose of holding the sleeve valve in position within the tubular journal 15 a pin 25 projects inwardly from the valve and engages in an arcuate slot 26 extending partially around the journal. This also prevents too great rotary movement of these parts relative to each other and it is to be noted that the pin is at one end of the slot when the openings 15' and 17 are exactly in registry.

Since the tone arm has no vertical movement provision is made to ensure proper contact of the needle with the record R. To that end one side of the reproducer is provided with a weight 27 as shown, this weight also serving as a handle for manipulating the reproducer and tone arm.

From an inspection of Figures 1 and 4 it will be plain that shifting the position of the pointer on the graduated arc will effect variation in the position of the valve and consequently in the effective area of the passage between the reproducer and tone arm. Moreover, if the reproducer be turned up towards the position shown in Figure 2, to change needles the pointer end 23 will first move around and engage the stop 24, since 110

the valve will turn through friction with the journal 15. Continuation of the movement of the reproducer will move the journal independently of the valve till the valve 5 and journal ports are brought into full registry, further movement being prevented by the action of the pin 25 and slot 26. Thus, when the reproducer is turned down again to place the needle on the record 10 the communicating passage will be fully opened.

There has thus been provided a simple and efficient device of the kind described and for the purpose specified.

15 It is obvious that minor changes may be made in the form and construction of the invention without departing from the material principles thereof. It is not therefore desired to confine the invention to the exact 20 form herein shown and described, but it is wished to include all such as properly come within the scope claimed.

Having thus described the invention, what is claimed as new, is:—

25 1. In a phonograph, a tone arm, a reproducer carried by the tone arm, a volume regulating valve between the reproducer and tone arm, means exterior of the tone arm for regulating and indicating the position of the 30 valve with reference to the reproducer, and other means associated with the last mentioned means and arranged to move the valve to fully opened position upon movement of the reproducer to needle changing 35 position.

2. In a phonograph, a tone arm mounted

for horizontal swinging movement and restrained from vertical swinging movement, a reproducer mounted at the end of the tone arm for rotation about a horizontal axis, 40 said reproducer having a hollow journal having port communication with the tone arm, a valve in said journal controlling the port communication, means exterior of the tone arm for regulating and indicating the 45 position of the valve with reference to the reproducer journal port, and other means associated with the last mentioned means and arranged to move the valve to fully opened position upon movement of the reproducer to needle changing position.

3. In a phonograph, a tone arm mounted for horizontal swinging movement and restrained from vertical movement, a journal bearing at the free end of the tone arm and 55 having a port communicating with the tone arm, a reproducer, a hollow journal leading from said reproducer and provided with a port normally registering with the bearing port, a sleeve valve rotatable within the 60 journal and having a port movable into and out of registry with the journal port, means exterior of the tone arm for moving the valve, and other means associated with the last mentioned means and arranged to move 65 the valve to fully opened position upon movement of the reproducer to needle changing position.

In testimony whereof I hereunto affix my signature.

EDMOND KUHN
